UNITED STATES PATENT OFFICE.

CHARLES N. WAITE, OF NEWTON, MASSACHUSETTS.

INSULATED CONDUCTOR.

SPECIFICATION forming part of Letters Patent No. 512,417, dated January 9, 1894.

Application filed February 20, 1893. Serial No. 463,070. (No model.)

To all whom it may concern:

Be it known that I, CHARLES N. WAITE, a citizen of the United States, residing at Newton, in the county of Middlesex and State of Massachusetts, have invented certain new and useful Improvements in Insulated Conductors, of which the following is a specification, reference being had therein to the accompanying drawing.

10 In the manufacture of chlorine by the electrolysis of alkaline chlorides, the chlorine is conducted from the cells preferably by means of lead pipes. I have found it desirable to insulate these lead gas conductors electrically.

15 My invention has for its object to provide a proper insulation for such gas conductors and it consists of means for that purpose as hereinafter described and the novel features of which are pointed out in the claims which 20 are appended hereto and made a part hereof.

In the accompanying drawing, I have shown my device in the best form now known to me, and in the following specification I will refer to said drawing in which I have shown a section of two parts of a lead pipe or gas conductor which are connected and which are insulated at the joint by the employment of my device.

Referring to the drawing, P P' are sections 30 of the lead gas conductor. The part P' is provided with a cup-shaped enlargement b which is designed to receive the end of the other section of the gas conductor P, as also the insulating material.

35 a is a ring or wicking of asbestos, which is interposed between the end of the section P and the cup-shaped enlargement b. Above the asbestos ring is a mass of Trinidad asphalt d, or other similar material, which is not affected by the chlorine, and which serves to seal the joint. The ring of asbestos serves to hold the melted pitch or asphalt d after it has been placed within the cup b and around the end of the section P of the gas conductor, 40 until the pitch has had time to cool and harden. It will be noted that the end of the section P of the leaden gas conductor projects downwardly below the asbestos ring. This is for the purpose of preventing any condensed vapor from coming in contact with the 50

asbestos insulation and thereby forming an electrical connection between the two sections of the conductor.

It will be obvious that the size and shape of the conductor may be varied as desired. 55

What I claim is—

1. A gas conductor consisting of two or more sections, the end of one of the sections being enlarged to receive the proximate end of the other section, and having within the enlargement a ring or layer of asbestos and a mass of asphalt, or similar substance, which will seal the joint, said asbestos and asphalt being interposed between the proximate portions of the sections of the conductor, substantially 60 as and for the purposes set forth.

2. A metallic gas conductor consisting of two or more sections, one of said sections being enlarged at the end to receive the end of the other section and having within the enlargement a layer of insulating material interposed between the proximate portions of the sections, substantially as and for the purposes set forth. 70

3. A metallic gas conductor consisting of 75 two or more sections, one end of said sections being enlarged at the end to receive the end of the other section, and a mass of insulating material and of sealing material interposed within the said enlarged end between the proximate portions of the said sections whereby the same are insulated and the joint sealed, substantially as set forth.

4. A metallic gas conductor composed of 85 two or more sections, one of said sections having an enlarged end to receive the end of the other section, and a layer of insulating material interposed between the proximate portions of the ends of said sections, the end of that section which is received within the enlarged end of the other section extending past the insulating material whereby condensed vapor is prevented from collecting on the insulating material, substantially as set forth. 90

In testimony whereof I affix my signature 95 in presence of two witnesses.

CHARLES N. WAITE.

Witnesses:

WM. A. MACLEOD,
ROBERT WALLACE.
